CLOTHES-WASHING MACHINE HAVING RECIPROCATING CLOTHES RECEPTACLE WITH RESTRICTED PASSAGEWAY

Arthur D. Lund, Minneapolis, Minn., assignor to Solar Corporation, Milwaukee, Wis., a corporation of Delaware

Application March 17, 1944, Serial No. 526,859

12 Claims. (Cl. 68—23)

1
This invention relates to washing machines particularly for home or domestic use, and of the general type in which the clothes are washed, rinsed, and centrifugally dried in the same receptacle.

The principal feature of the invention is the provision of a perforate clothes receptacle mounted for vertical reciprocation in a surrounding tub, partially filled with the cleansing fluid, and with baffle means arranged in such manner as to produce a new, novel, and highly efficient washing action when the receptacle is so actuated.

Other objects are to provide improved, yet simple and practical mechanisms for mounting and actuating the receptacle, both for washing and rinsing, as well as for drying, so that the various operations may be effectively performed in proper sequence and for such durations as may be found desirable.

Further and more detailed objects will appear in the course of the following specification, reference being had to the accompanying drawings, wherein like parts are designated by like characters, and in which—

Fig. 1 is a sectional elevation taken centrally through a washing machine exemplifying a preferred embodiment of the invention, this view being on the line 1—1 in Fig. 2.

Fig. 2 is a sectional plan view as seen on line 2—2 in Fig. 3, with fractional portions broken away.

Fig. 3 is a sectional elevation of the lower part only of the machine, as seen on the substantially diagonal section line 3—3 in Fig. 2.

Fig. 4 is a top or plan view of the machine, as shown in Figs. 1-3, but with various portions broken away for purpose of illustration.

Fig. 5 is an enlarged sectional elevation on line 5—5 in Fig. 2.

Fig. 6 is a detail section on line 6—6 in Fig. 5.

Fig. 7 is an enlarged detail section on line 7—7 in Fig. 1.

Fig. 8 is a sectional detail corresponding to a portion of Fig. 1, but showing a modification of the clothes receptacle adjacent the center seam.

Fig. 9 is a central sectional elevation through a modified construction of washing machine.

Fig. 10 is an enlarged sectional elevation, taken diametrically through the transmission mechanism in the lower end of the machine shown in Fig. 9.

Fig. 11 is a detail plan view on line 11—11 in Fig. 10.

Fig. 12 is a sectional plan view through the

2
clothes receptacle in Fig. 9, on a reduced scale, showing the circular shape or contour of the opening within the baffle through which water and the articles to be washed are passed during the washing operation.

Figs. 13 to 17, inclusive, are similar to Fig. 12, but show modified forms of baffle.

Referring to the drawings more particularly and by reference characters, and with particular reference to the disclosure in Figs. 1 to 7, inclusive, A designates an upright outer shell or housing which, as shown, is square in cross section, and is mounted on a rectangular base B, being closed at its top by a cover C. A stationary tub D is mounted within the housing, and within this tub is disposed a perforated clothes receptacle or basket E, mounted both for vertical reciprocation and for rotary or spinning motion.

The housing A fits snugly over the base frame 20 B to which it is rigidly secured, and its top 20 has a circular opening closed by the cover C which is preferably hinged as at 21. This cover has an internal flange 22 provided with a gasket 23 closing against a bead 24 formed at the upper end of tub D and which is sealed with respect to the casing by a gasket 25, as shown in Fig. 1. Immediately below the bead 24 the tub D has an annular groove 26 in which is seated a perforated pipe 27 having an extension 28 (Fig. 4) for connection with the hot and cold water supply, the pipe 27 providing all water for the washing and rinsing operations.

At a lower point the tub D is provided with an annular groove 29, the purpose of which will presently be described, and at its bottom the tub is rigidly secured, by screws 30, to a central plate member 31, formed as an integral part of the base frame B. The plate 31 has an outer annular groove 32, into which the tub drains, and this groove has an outlet spout 33 leading into a circulating pump 34, having an outlet 35, and driven by a small motor 36 which, with the pump, may be hung on the spout 33. The purpose of the pump and motor is to enable quick draining of the tub, and where desirable may pump the water into an elevated drain or receptacle. The pump, when idle, may serve as a check to prevent draining when the machine is in use, or if necessary a suitable valve may be inserted. Ordinarily, however, a hose is attached to the outlet 35, and with one end hung up in a raised position will operate to keep the water at any level desired.

The plate 31 is further provided, concentrically within the groove 32, with an annular recess

or channel 36, supporting a circular cushion 37, up through which extends a tubular standard 38. This standard supports the clothes receptacle E but neither rotates nor reciprocates with it. While having guiding support at its bottom the standard is primarily supported on the cushion 37 by a flanged nut 39 which screws on the standard and has inner and upper face contact with the cushion, as shown in Fig. 1. It will also be noted that the center opening in plate 36 is somewhat larger than the outer diameter of the enclosed portion of the standard. Thus it will be evident that the cushion 37 is so disposed that it can take up vertical as well as radial vibrations imparted to the standard by action of the receptacle E, and this is regarded as a feature of the invention.

The receptacle E has a sleeve 40 which surrounds the upper portion of the standard and this sleeve is free to reciprocate vertically or rotate on the standard a bushing 41 forming bottom contact between the two.

At its upper end the sleeve 40 has a cap that seats in the grooved upper end of a sleeve 42 that projects upwardly within and above the standard, and the two sleeves are rigidly yet releasably secured together by a nut 43. This nut also operates to secure an annular baffle member F having a cylindrical part 44 that fits over a recessed upper end part of the sleeve 40.

The inner sleeve 42 extends through a packing gland 45 near the upper end of the standard and this gland is held in a compressed sealing condition by a spring 46 held down by a bushing 47 threaded into the upper end of the standard. It will thus be seen that as the inner sleeve 42 is vertically reciprocated, or rotated, it will correspondingly reciprocate, or spin, the basket E and baffle F.

The clothes receptacle or basket E is preferably formed in upper and lower sections having integrally connected flanges forming an annular ledge or flange 48. When the basket is in its lowermost position, as shown in Fig. 1, this flange is radially within the tub groove 29 thus leaving an annular passageway between the tub and basket past the flange. When the basket is raised, however, as indicated in Fig. 8 the flange 48 substantially closes such passageway except for necessary slight clearance. It may here also be noted that adjacent the flange 48 the basket is provided with a pair of inwardly formed beads 49 which are more pronounced in Fig. 8 than in Fig. 1.

From the flange 48 upwardly the side walls of the clothes receptacle imperforate but the top is perforated, as at 50, including a lid 51 which is hinged at 52 and provided with a latch handle 53 opposite the hinge.

The lower section of the receptacle E has its bottom and side walls perforated as at 54, and the bottom is also radially ribbed as at 55 for reinforcing purposes and also to break up the otherwise flat or plane contour of the clothes supporting surface. The baffle member F is somewhat bell-shaped, both above and below, with the upper surface preferably at a steeper inclination than the lower, so as to facilitate the gravitational movement of the contents downwardly between the baffle and beads 49 when the receptacle is moved upwardly.

Returning now to the center construction it will be seen that sleeve 42 extends downwardly into the enlarged lower section of standard 38 and over an upstanding shaft 56 the lower end

of which is anchored in the hub of a pulley 57. Shaft 56 and sleeve 42 are splined together as at 58, so that the shaft will drive the sleeve in any position to which the latter may be vertically adjusted. At its bottom end the sleeve 42 is connected by bearing cage 59 to a collar 60 (Figs. 5-6) having diametrically opposed studs 61 extending out through vertical slots 62 in the standard 38. The bearing 59 is of the self-aligning type capable of imparting both axial and radial thrust. Thus, when collar 60 is vertically adjusted, and without rotation, it will raise and lower sleeve 42 without interfering with rotation of the latter by the shaft 56.

In order that shaft 56 and pulley 57 may also freely rotate with respect to standard 38 another bearing ring is inserted at 63, while a third roller bearing between the pulley hub and base frame is inserted at 64. This latter bearing is secured in place from the bottom of the machine, and by removing screws 65 and nut 65a the entire center construction may be released for upward removal when so desired.

Pulley 57 is driven by belt 66 from a pulley 67 on the shaft of a motor 68 hinged at 69 and held in belt tightening position by spring 70.

Vertical reciprocation of the sleeve 42 and its supported clothes receptacle E is produced by securing the collar studs 61 in the forked arms of a lever 71. This lever is attached at its opposite end to an oscillatable fulcrum link 72, connected to the base B, and, at an intermediate point, is connected by link 73 to the crank arm 74 of a transmission unit 75 having a speed reduction worm and gear driven by shaft 76 from motor 77, such motor being rigidly mounted to a strut member 78 of the base frame. The double link arrangement 72 and 73 is such as to allow the necessary rectilinear movement of the studs 61 and collar 60.

The operation of the preferred form of the machine, as thus described, may be explained as follows:

With the cover C and lid 51 open a predetermined amount of soap is placed in the bottom of the receptacle E and the latter is then filled with dry clothes or other fabrics to be cleaned preferably up to the flange line 48. The lid 51 and cover C are then closed down, whereupon the washing action may be started by closing a circuit to the motor 77. Water is then turned into the tub through inlet 28 and perforated ring 27 in sufficient quantity and at desired temperature. This water filters down through and past the clothes where it reaches the soap which quickly dissolves under the combined action of heat and agitation. It may here be noted that with the washing action herein produced a comparatively small amount of soap and water, or suds, is required to effectively and thoroughly clean a batch of clothes.

As the motor 77 rotates the shaft 76 it operates through the transmission 75, crank 74, link 73, and lever 71, to vertically reciprocate the sleeve 42 over a distance corresponding to the length of slots 62. As the sleeve then moves up and down it carries with it the receptacle or basket E and the baffle F, but neither of these members rotate or oscillate during the washing operation.

When the receptacle starts upwardly the flange 48 leaves the groove 29 and therefore substantially closes the annular space between the receptacle and tub D, thus effectively shutting off circulation through this space. Consequently air

pressure is developed in the upper end of the receptacle, thus supplementing gravity in forcing all water, suds and clothes in the upper part of the receptacle down through the annular space between the baffle F and the receptacle wall. This action is obviously negligible on the first up-stroke, as the contents are already at the lower level, but is of utmost importance in the subsequent operation.

The reverse or down-stroke is equally, if not of greater importance, since here the effect of gravity must be entirely overcome to raise the contents into the upper section of the receptacle. On the down stroke the flange 48 exerts a decided pumping action and forces the water and suds in through the perforations 54 setting up pressure and turbulence within the lower section of the receptacle that circulates the water and clothes upwardly into the upper chamber. This movement or circulation is in part only relative with respect to the baffle F, as the latter, in effect moves downwardly through the contents.

As the action continues the contents are alternately moved into the upper and lower compartments of the basket, and this produces a very efficient washing operation. With each upward stroke the clothes are brought into close proximity or contact with the perforated sides and bottom of the receptacle, and with each downward stroke they are forced up into contact with the perforated top of the container. The friction developed on such contacts is virtually negligible, however, with a result that there is no objectionable wear or tear on the clothes.

The significant and important feature of the operation lies in the fact that at the end of each up and down stroke the clothes are spread out over a large area, so as to make full area contact with the suds, but when passing from one chamber to the other they are forced through the restricted annular space between the baffle F and ribs or beads 49, thus moving at increased speed and with a highly effective squeezing and flexing action forcing the fluid through all the fibers of the articles being washed. This repeated squeezing, flexing and expanding action while energetic and effective does not tend to tangle or distribute the clothes unevenly about the sides, but rather tends to impart a symmetrical distribution to them, and this is particularly desirable since it insures uniformity of cleansing and also leaves the clothes in well balanced condition for the spinning or drying operation.

It may also be observed that the movement of the clothes through the restricted passage-way is facilitated by the fact that the pumping action in one direction is supplemented by a partial suction or vacuum action in the other direction thus in considerable measure utilizing the vacuum principle of cleansing which is recognized in the art as a highly efficient theory. It will also be noted that the side walls of the upper portion of the receptacle are not perforated since this section is above the normal water level, when at rest, and this condition accelerates the upward and inward movement of the water and clothes on the down stroke of the receptacle. Furthermore perforation of the upper wall is unnecessary for centrifuging purposes because of the fact that during that operation the water, as noted, does not reach that level.

Conversely, the side walls and bottom of the lower receptacle section are profusely perforated since that is necessary for speedy drying of the

clothes; and also to facilitate the movement of the water therethrough to quickly produce suds.

When the predetermined washing period has expired the motor 71 is stopped and drainage of the water is effected either solely by gravity or preferably by starting the motor 36 and pump 34 in which event the water can be elevated to a storage receptacle if desired for further use. Concurrently with such drainage it may be desirable to also start the motor 68 thus spinning the receptacle. Such spinning would not be for drying purpose but merely to insure discharge of scum which may accumulate on the surface of the water above the clothes.

15 After drainage of the wash water has been sufficiently completed rinse water is injected into the pipe 27 and this not only supplies a sufficient quantity for rinsing the clothes but because of the arrangement of the perforations in this pipe effectively flushes the entire machine. The clothes rinsing operation is performed exactly like the washing operation except that possibly more water is used and, when completed, the rinse water is similarly emptied from the machine.

20 To dry the clothes it is only necessary to start the motor 68, which spins the receptacle E, and let it run until the clothes have become as dehydrated as the operator wishes.

With further reference to structural features 30 and advantages it will be seen that since the upper and lower bearings (47 and 59, 63) are widely separated and very sturdy, steady and mechanically efficient structure is obtained. It will also be noted that for inspection or repair purpose 35 the machine can be disassembled and reassembled very quickly and easily, it only being necessary to remove the unit 43 to free the upper parts, and by removing nut 65a the entire center unit may be lifted out.

40 Turning now to the modified construction shown in Figs. 9 to 12, inclusive, of the drawings, it will be observed that the housing 80 is supported on the base frame 81, and both of these units support the tub 82 much as in the preferred form.

45 The clothes receptacle 83 is also substantially duplicated except for the baffle which, in this instance is in the form of an inwardly extending ledge mounted on the side wall so as to form a restricted inner opening 85 for the passage of water and clothes, in place of an outer annular passage.

The receptacle 83 is mounted on a hollow spindle 86 the upper end of which rotates in bearings 87 housed within a sleeve 88. This sleeve has a flange 89 at its upper end while a complementary flange 90 extends from a packing unit 91 threaded on the lower end of the sleeve. The flanges 89 and 90 are clamped against upper and lower surfaces, respectively, of a pair of circular cushion members 92, having tapered peripheral surfaces conforming with wedge acting surfaces of the base plate 93 thus tightly yet resiliently supporting the clothes receptacle.

55 The spindle or sleeve 86 extends down over an upstanding shaft 94, the lower end of which is rigidly secured by nut 95 in the hub 96 of a pulley 97. The hub 96 rotates in a self-aligning bearing cage 98 secured in the base frame 81 by screws 99 and retention ring 100. Pulley 97 is driven by belt 101 from pulley 102 of motor 103, and the pulley in turn rotates shaft 94 and the spindle 86 splined thereto as at 104. The drive connection for spinning the clothes receptacle 70 is thus completed.

The receptacle 83 is rectilinearly reciprocated by a motor 105 driving a shaft 106 to operate through a worm-gear drive 107, crank 108, link 109, and a lever 110, fulcrumed at 111 and connected by links 112 to studs 113 of a collar 114. This collar includes a bearing cage 115 in which the spindle 86 may rotate but which is held against vertical movement with respect thereto.

The modified forms of baffles 84a, 84b, 84c, 84d, and 84e, shown in Figs. 13 to 17, inclusive, define restricting passageways of different shapes or contours, and in some instances may be found preferable to the styles shown in Figs. 1 and 9.

It is to be understood that various other and further modifications may be made in the construction and details of the machines as herein described, providing such modifications come within the spirit and scope of the appended claims. Having now therefore fully disclosed the preferred embodiments of the invention, what I desire to protect by Letters Patent and claim is:

1. In a washing machine, a tub, a tub, a perforated receptacle mounted for reciprocating movement in the tub and in sufficiently close proximity to the inner wall of the tub to restrict the flow of fluid between the tub and receptacle in the directions of reciprocation, said receptacle having end chambers connected by a restricted passageway through which the articles to be washed together with the washing fluid will pass back and forth from one chamber to the other and in directions opposite to the reciprocatory movements of the receptacle, said restricted passageway operating to constrict and flex the articles as they pass from one chamber to the other, and means for reciprocating the receptacle to perform the washing operation.

2. In a washing machine, a generally vertical tub, a receptacle mounted for vertical reciprocation in the tub in close proximity to the wall thereof so as to restrict the flow of fluid vertically between the tub and receptacle during such reciprocation, said receptacle having upper and lower perforations through which fluid and air may be circulated in and out under pumping and suction action produced by the piston acting reciprocations of the receptacle in the tub, and baffle means within the receptacle separating it into two chambers connected by a restricting passageway through which articles being washed will alternately pass from one chamber to the other and be intermittently constricted during such passage.

3. In a washing machine, an upright, vertically elongated tub adapted to contain cleaning fluid in its lower part, a receptacle mounted in the tub and having a perforated lower portion adapted to be submerged in the fluid, means for vertically reciprocating the receptacle in the tub and in close proximity to the wall thereof to produce a pumping action whereby the fluid and materials to be cleaned will be alternately actuated from end to end in the receptacle by suction and compression at opposite ends of the receptacle, and a baffle member disposed in a transverse plane within the receptacle to divide the same into end chambers connected by a restricted passageway.

4. In a clothes washing machine, an upright tub, a perforated receptacle of substantially the same external diameter as the internal diameter of the tub mounted for vertical reciprocation within the tub to wash the clothes, and a transversely disposed member arranged within the receptacle to form upper and lower chambers therein connected by a clothes passageway the

cross sectional area of which is substantially less than the cross sectional area of said chambers whereby the clothes will be intermittently compressed as they travel back and forth through the passageway under reciprocating movements of the receptacle.

5. In a washing machine, a supporting frame, a tub thereon, a vertical spindle mounted in the frame, a perforated clothes washing receptacle mounted on the spindle, means for reciprocating the spindle for piston-like action in the tub and receptacle to wash clothes in the latter, and a baffle disposed within the receptacle transversely with respect to the direction of oscillation to separate the receptacle into two clothes receiving chambers connected by a passageway, an edge of the baffle defining part of said passageway, and said baffle having upper and lower surfaces converging toward said edge.

20 6. In a washing machine, an upright tub having a horizontally extending groove about its inner wall surface, a perforated receptacle mounted for vertical reciprocation and rotary movement in the tub, said tub and receptacle being peripherally spaced, and a flange extending from the receptacle toward said groove when the receptacle is in a predetermined vertical position whereby a passageway will extend about the edge of the flange, said flange being operative to substantially prevent circulation of fluid vertically through the space and passageway when the tub is moved from said predetermined vertical position.

7. In a washing machine, a tub, a perforated receptacle mounted for axial reciprocation in the tub and normally having substantial peripheral sealing engagement with the tub whereby the receptacle will have a piston action therein to force fluid through the perforated receptacle when the latter is reciprocated, means for reciprocating the receptacle to produce the washing action, means for spinning the tub when in a predetermined axially stationary position to extract fluid from the receptacle and articles having been washed therein, and means operative upon positioning the receptacle in said axially stationary position for interrupting said substantial sealing engagement and providing full clearance between the receptacle and tub.

50 8. In a washing machine, a generally upright tub, a perforated receptacle mounted for axial reciprocation in the tub and for piston like action therein to force cleaning liquid through the receptacle and thereby cleanse articles therein, means for alternately reciprocating the receptacle in the tub, means for spinning the receptacle to extract moisture therefrom when the receptacle is in an axially stationary position in the tub, and means operative upon bringing the receptacle to rest axially with respect to the tub and in said axially stationary position to provide peripheral clearance between the tub and receptacle whereby the receptacle may spin out of contact with the tub.

55 9. In a washing machine, a generally upright tub, a perforated receptacle mounted in the tub for vertical reciprocation therein to perform the washing operation and for spinning action when in a vertically stationary position in the lower end of the tub to centrifugally extract moisture therefrom, means for vertically reciprocating the receptacle, and means for spinning the receptacle, said receptacle and tub being so formed that they will have substantial peripheral sealing engagement with respect to each other during

the washing operation but will be free of peripheral frictional contact during the spinning operation.

10. In a clothes washing machine, a tub for containing cleansing fluid, a perforated clothes receptacle mounted for rectilinear reciprocating action within and in close proximity to the wall of the tub whereby the cleansing fluid will be pumped through the receptacle to cleanse the clothes therein as it passes therethrough, said receptacle having walls entirely enclosing its interior, and said receptacle having connected end chambers defined in part by a baffle member disposed substantially midway between the ends of the receptacle and which baffle member defines a restricted passageway whereby the clothes are constricted and flexed as they alternately pass from one chamber to the other.

11. In a clothes washing machine, a tub for containing cleansing fluid, a perforated clothes receptacle mounted for rectilinear reciprocating action in effective sealing contact with the tub whereby the cleansing fluid will be pumped through the receptacle to cleanse the clothes therein as it passes therethrough, said receptacle having walls entirely enclosing its interior, and said receptacle having connected end chambers defined in part by a baffle member disposed substantially midway between the ends of the receptacle and which baffle member defines a restricted passageway whereby the clothes are constricted and flexed as they alternately pass from one chamber to the other, said baffle member being supported axially within the receptacle and having outwardly converging upper and lower surfaces adapted to guide the clothes into said restricted passageway.

12. In a clothes washing machine, a tub for

containing cleansing fluid, a perforated clothes receptacle mounted for rectilinear reciprocating action in the tub and in effective sealing proximity thereto whereby the cleansing fluid will be pumped through the receptacle to cleanse the clothes therein as it passes therethrough, said receptacle having walls entirely enclosing its interior, and said receptacle having connected end chambers defined in part by a baffle member disposed substantially midway between the ends of the receptacle and which baffle member defines a restricted passageway whereby the clothes are constricted and flexed as they alternately pass from one chamber to the other, said baffle member being supported axially within the receptacle and having an outwardly sloped upper surface adapted to direct the clothes into said passageway.

Certificate of Correction

Patent No. 2,439,215.

April 6, 1948.

ARTHUR D. LUND

It is hereby certified that errors appear in the printed specification of the above numbered patent requiring correction as follows: Column 6, line 57, for "unit 91" read *nut 91*; column 8, line 11, claim 5, strike out the words "for piston-like action in the tub" and insert the same in line 10, same claim, after "spindle" and before the comma; and that the said Letters Patent should be read with these corrections therein that the same may conform to the record of the case in the Patent Office.

Signed and sealed this 22nd day of June, A. D. 1948.

[SEAL]

THOMAS F. MURPHY,
Assistant Commissioner of Patents.
